UNITED STATES PATENT OFFICE.

FREDERICK JOHN TURNER BELL AND HARDY CECIL BELL, OF ASHTON-UNDER-LYNE, ENGLAND, ASSIGNEES TO TWIN BOBBIN SEWING MACHINE COMPANY LIMITED, OF ASHTON-UNDER-LYNE, ENGLAND.

SEWING-MACHINE.

1,307,842.

Specification of Letters Patent. Patented June 24, 1919.

Application filed August 3, 1915. Serial No. 43,376.

To all whom it may concern:

Be it known that we, FREDERICK JOHN TURNER BELL and HARDY CECIL BELL, both subjects of the King of Great Britain and 5 Ireland, and both residents of Ashton-under-Lyne, in the county of Lancaster, England, have invented new and useful Improvements in Sewing-Machines, of which the following is a specification.

10 This invention relates to lock stitch sewing machines of that type known as two reel, *i. e.*, in which a reel, bobbin, cheese, or the like of thread is used for the underthread in the machine in the form in which it comes 15 from the manufacturer. The particular type of two reel machine to which these improvements relate is that in which the reel of underthread is contained within a rotary shuttle preferably obliquely disposed and 20 rotated through the medium of pins projecting from arms or from a disk mounted on a suitable driving shaft.

This invention relates to a form of rotary shuttle and also a carrier for the reel of 25 underthread and to various accessories therefor which reduces the size of the loop of the needle thread which is passed over the carrier of the reel of underthread in machines of the two reel type and facilitates its passage thus reducing the risk of breakage. 30 The invention also relates to further improvements hereinafter more fully described.

In the accompanying drawings,

Figure 1 shows a combination of the parts, 35 to which our improvements relate, assembled in side elevation,

Fig. 2 is a front elevation of Fig. 1,

Figs. 3-31 illustrate the parts separately and some modifications of details, and,

40 Figs. 32-35 the rotary shuttle in various positions during its rotation around the reel carrier.

The rotary shuttle and holder for the carrier of the reel of underthread, separately 45 shown in front elevation in Fig. 3 and in side elevation in Fig. 4, consists of a truncated conical, domed or equivalently shaped metallic shell through the opening of which the reel and its carrier can pass into and be

contained within the rotary shuttle. The 50 base of the rotary shuttle A is cut away at one part to form a hook A¹ to enter and engage with the loop of the needle thread. In a modified form the rotary shuttle may be suitably notched and adapted to be fitted 55 with a hook in any suitable manner, for instance as shown in Fig. 5, and which hook can then be renewed as required. Just past the hook the shuttle is provided with an inclined plate or spreader A² extending preferably, up to the front edge of the reel carrier. The rotary shuttle may be furnished with a hard steel ring A³ around its base, Fig. 6, and the race in which it rotates may be fitted with a similar interchangeable steel 60 ring, if desired. The base, the conical shell and the guide plate or spreader A² of the rotary shuttle A, may be produced as separate 65 parts and fitted together as shown in Fig. 7, or the base and conical shell may be made in 70 one part and the guide plate or spreader A² may be attached to the shuttle in such a way as to be easily detachable, as shown in Fig. 7. A detachable guide plate or spreader for 75 the case A is separately shown in Figs. 22 and 23.

The race for the rotary shuttle, shown in Fig. 8 in part elevation and in Fig. 9 in side elevation, in the construction shown consists of a ring B which by means of suitable arms 80 B¹ is connected with a hub B² through which the driving shaft S passes and which is secured in any suitable manner, for instance by being clamped in a split bearing C, Figs. 1 and 2. The ring B is not at right angles 85 to the hub B² but is obliquely disposed to it. At its highest point and in the rear the ring B is fitted with a guard plate D inclined toward the back of the machine which prevents the thread of the needle loop flying 90 toward and becoming entangled with the driving pins. The face of the ring B is fitted with a cover or cap of slightly smaller inner diameter than the inner diameter of the ring, which keeps the rotary shuttle in position within the race. A flange on the cover or cap may be provided with bayonet slots 95 adapted to engage with pins disposed on the

circumference of the ring. Any other suitable means may be employed for securing the cover or cap in position in such a manner as to be rapidly removable by the operator. 5 Preferred means are shown in Figs. 8 to 11 and 25 and 26. Referring to Figs. 8 and 9 the ring B is provided with three projections B³ on its periphery, the two upper ones of which are undercut. The cover used in conjunction with these projections is shown in 10 Figs. 10 and 11. It consists of a plain ring E which is slipped under the undercut projections B³ at the top of the ring B and rests on the projection on the bottom. It is secured in this position by a screw Z, Figs. 1 15 and 2, passing through a recess E¹ and into a tapped hole in the ring B. To facilitate the putting in place of the cover E its periphery may be provided with one or more recesses such as E², Fig. 10. By putting the 20 cover on so that one of these recesses fits over the lower projection B³ the cover can be put on the face of the ring B. It is then pushed upward under the overhanging faces 25 of the upper projections B³ and brought into the proper position by a slight angular movement. By removing this cover the rotary shuttle can easily be taken out. Referring to Figs. 25 and 26, the ring E is 30 provided with recesses b into which fit the overhanging inner edges b¹ of the projections B³.

Between the cover or cap and the face of the race a thin, preferably hardened, steel 35 ring such as F, Figs. 12 and 13, may be inserted to reduce or take up wear. The position of this ring is indicated in broken lines F in Fig. 9.

Within the space formed by the arms connecting the race with its hub, are mounted, 40 upon the driving shaft the arms carrying the driving pins which engage with and become disengaged from the rotary shuttle. As shown in Figs. 14 and 15 these pins G are 45 preferably made integral with the arms G¹. The pins G are split or bifurcated whereby a smooth and light engagement of the pins with their holes in the rotary shuttle is insured and an almost noiseless drive is obtained as backlash is prevented.

Between the driving pins and the rotary shuttle and rotating with them there may be arranged a dished or flat plate such as H, 55 Figs. 14 and 15, which prevents ballooning of the thread.

After the hook of the rotary shuttle has engaged the loop of needle thread the front part of the loop is carried around at the base of the hook as shown in Fig. 32. After the 60 hook has described an angle of about 140° the front of the loop starts slipping along the leading edge of the guide plate or spreader A², see Fig. 33. At an angle of about 180° the loop is half way off the ro-

65 tary shuttle guide plate or spreader A², see Fig. 34, and commences to slip around the face of the reel carrier case. To facilitate this the stationary reel carrier J, Figs. 16 and 17 and Figs. 30 to 33, is provided with an inclined guide plate J¹ or spreader which 70 extends from the front of the reel carrier toward the back and downward to the front where the needle thread loop slips off the reel carrier. This inclined plate or spreader J¹ on the reel carrier is so arranged 75 that the needle thread loop is thrown on and over it by the rotating shuttle and its outer part slides along it as it slips off the shuttle. As shown in Fig. 34 the front part of the 80 loop is half way off the shuttle guide plate or spreader A² and half way on the reel carrier guide plate or spreader J¹. In Fig. 85 35 the front part slips off both guide plates or spreaders and is pulled up. The back part of the needle thread loop at the same 90 time slides along the rear edge of the recess or notch in the rotary shuttle till it reaches the bottom of the recess and is carried around the back of the rotary shuttle in advance of the front part of the loop, as shown 95 in Figs. 32 to 35 until it slips off the shuttle. The guide plate or spreader J¹ may be detachable from the reel carrier case J. Such a plate or spreader is shown separately in Figs. 30 and 31.

95 The reel carrier J is furnished with a central tubular piece K which fits on a pin or holder L in the center of the rotary shuttle, Figs. 3 and 4. To prevent the reel carrier from slipping off the pin or holder a suitable spring catch on the front of the reel carrier engages a groove L¹ in the pin or holder. The spring catch shown in Fig. 17 consists of a plate L² provided with a hole and urged sidewise by a spring l engaging 100 at one end a notch l¹ in the plate L², Fig. 29, so as to obstruct the hole L³ in the reel carrier. The tapered head of the pin or holder L when being introduced into the hole L³ displaces the plate L² against the resistance 105 of the spring which subsequently forces the plate L² back and into the groove L¹ of the pin or holder when the reel carrier is firmly held within the rotary shuttle against falling out. When it is desired to take the reel carrier out the plate L² is pressed inward 110 against the resistance of its spring until finally the holes in the plate L² and the carrier coincide and the reel carrier can easily be pulled off the pin or holder of the rotary 115 shuttle. Other means may be employed for this purpose and we make no claim to this device *per se*.

To prevent rotation of the reel carrier J a delivery eye or like part M, Fig. 16, may 120 fit into a notch N in the cover or cap E of the race, Figs. 2 and 10.

The tubular piece K of the reel carrier J

has mounted so as to rotate upon it three or four spring bows O, Fig. 16, by means of which the reel of thread slipped over them is secured and centrally held in position. 5 The middle parts of these bows which may be joined together at both ends by collars are made flat to prevent rocking of the reel upon the bows.

The thread T¹ from the reel contained in 10 the reel carrier is passed through a narrow slit P in the cylindrical casing of the reel carrier J, Fig. 16, into a wider slot P¹ which extends almost from end to end of the reel carrier casing and from there the thread 15 passes to a guide or barb P² situated above and at about the middle of the slot P¹. The thread as it is drawn off the reel passes from end to end of the slot P¹ according to whether it is drawn off from one end or the 20 other of the reel whereby friction is reduced and unnecessary straining of the thread avoided. The slot P¹ is preferably curved to conform with an arc described from the guide or barb P² as a center. The length of 25 the free thread between the slot and the guide will thus always remain equal. The guide or barb P² may be produced by stamping out a tongue from the reel carrier casing and suitably shaping it, or it may consist of a separate piece suitably attached to 30 the inside of the reel carrier casing and projecting through a slot in it.

From the guide or barb P² the thread passes through a groove in the reel carrier 35 casing to the front of the reel carrier where it passes under a barb U on the plate V¹, Fig. 29, covered by the plate V, Figs. 17 and 28, and under the tension regulating spring Q, Fig. 17, as separately shown in 40 Fig. 27, and thence to the delivery eye or like part M on the plate V. The tension regulating spring may be suitably placed on the part M which would be adapted to receive it. The screw Q¹ for adjusting the 45 tension regulating spring is easily accessible from the front or top of the machine and the tension of the underthread may thus easily be regulated without the necessity of taking out or moving the reel carrier.

50 The delivery eye or like part M to which the underthread passes may be provided with a straight groove M¹. At its end the eye is provided with a curl M², Figs. 18 and 19, which allows the thread to fall easily 55 into the groove but which retains it safely in position.

The groove may describe a spiral path, if desired, and the delivery end may be provided with an overlapping plate or other 60 retaining device than the one described.

The cover or cap of the race of the reel casing may be provided with a semi-circular or other suitably shaped plate R, separately shown in Figs. 20 and 21 and Figs. 1 and 2,

attached to the cover, which prevents the 65 thread of the needle loop from flying outward and becoming entangled with any part of the mechanism. The plate R can be attached to the cover or cap for the race in any suitable manner, one method being illustrated in the drawings. 70

We declare that what we claim is:—

1. In a sewing machine of the class wherein in a rotary shuttle is driven by driving pins engaging holes in the shuttle, the combination of a rotary shuttle with a reel carrier mounted within said shuttle, a spreader plate mounted on said rotary shuttle, and a spreader plate mounted on said reel carrier coöperating with said spreader plate on said 80 rotary shuttle for guiding the needle thread loop.

2. In a sewing machine of the class wherein in a rotary shuttle is driven by driving pins engaging holes in the shuttle, the combination of a rotary shuttle with flexible bifurcated driving pins engaging said shuttle, a shaft for said driving pins and a support for said shaft having parts carried thereby 90 for supporting said shuttle.

3. In a sewing machine of the class wherein in a rotary shuttle is driven by driving pins engaging holes in the shuttle, the combination of a rotary shuttle with flexible bifurcated driving pins engaging said shuttle, a 95 drive shaft for said pins, a support for said shaft having a raceway formed therein in which said shuttle is adapted to ride.

4. In a sewing machine of the class wherein in a rotary shuttle is driven by driving pins 100 engaging holes in the shuttle, the combination of a rotary shuttle with a part having a raceway in which said shuttle is revolvably mounted, a drive shaft and pins having flexible bifurcated ends engaging in the holes in 105 said rotary shuttle.

5. In a sewing machine of the class wherein in a rotary shuttle is driven by driving pins engaging holes in the shuttle, the combination of a rotary shuttle with a reel, a casing 110 for said reel, said casing having an arcuate shaped slot therein extending longitudinally across the casing, a delivery eye carried by said casing, a tension device arranged adjacent said delivery eye, and a guide carried 115 by said casing which carries the thread passing through said slot to the tension device from whence it is delivered to the eye.

6. In a sewing machine of the class wherein in a rotary shuttle is driven by driving pins 120 engaging holes in the shuttle, the combination of a rotary shuttle with a reel carrier within said shuttle said reel carrier having a surrounding casing, and a delivery eye for said thread carried by said reel carrier, said 125 delivery eye being open for a portion of its circumference.

7. In a sewing machine, the combination

of a shuttle having openings and flexible driving means engaging said openings.

8. In a sewing machine, the combination of a shuttle having openings and bifurcated driving pins engaging each of said openings.

9. In a shuttle for sewing machines, the combination of a shuttle with a part having a raceway in which said shuttle is mounted,

a detachable cover secured to said part for holding said shuttle in said raceway, and a 10 guard plate for the needle thread loop secured to said cover.

In witness whereof we have hereunto set our hands.

FREDERICK JOHN TURNER BELL.
HARDY CECIL BELL.
